J. J. HOELLE
DOMESTIC HAND TOOL

Filed Oct. 9, 1923

INVENTOR:

John Jacob Hoelle
By Richard A. Kier
Attest.

UNITED STATES PATENT OFFICE.

JOHN JACOB HOELLE, OF SYDNEY, NEW SOUTH WALES, AUSTRALIA.

DOMESTIC HAND TOOL.

Application filed October 9, 1923, Serial No. 667,466, and in Australia September 28, 1922.

This invention relates to a domestic hand tool in which the metal frame not only serves to support various implements, but is adapted to function as an implement and also as a member of other tools mounted on it.

Various forms of domestic hand tools are known in which implements, such as a corkscrew, a tin-opener, and a claw for removing crown corks from bottles, are mounted on a metal frame, but my device comprises, in addition to the corkscrew and the tin-opener, two broad-faced crown-cork removers adapted to remove crown corks of very different sizes, a crown-cork replacer, a fish-scaler or like scraper holder, a tack-hammer, a tack-lifter, and a straight-edged scraper or peeler, and is thus adapted for varied service in a household, flat, restaurant, or camp.

In the accompanying drawings

20 Fig. 1 is a side elevation;
Fig. 2 is a plan; and

Fig. 3 is a front end elevation of my tool.

The metal frame 10 is formed with three expanded portions or loops, one end loop 11 functioning as a crown cork replacer and also as a holder for a fish-scaler or like scraper. Between the other loops is riveted an L-shaped steel plate 12 of which one arm projects beyond the front end loop 13 and forms

30 the cutting blade 14 of the tin opener; the other arm 15 passes through the frame and is bent so that its flattened end 16 lies under the median line of the frame, said end also extending in a plane at right angles to the plane of the cutting blade and being inclined rearwardly with respect to the adjacent surface of the frame 10. This flattened and inclined end functions as a tack hammer, the mass of the plate 12 and frame giving suffi-

35 cient momentum to the blow when hammering.

The rear edge of the end 16 is provided with a V-shaped notch or claw 17 by means of which projecting tacks may be lifted.

40 The front edge 18 of the arm 15 is recessed so that the face of the hammer projects beyond its support 15. This projecting face, in conjunction with the front loop 13, forms a broad-faced crown-cork remover, and in use 45 obviates the distortion and tearing of a crown cork frequently associated with a claw-shaped crown-cork remover. The rear edge 19 of the arm 15 is similarly recessed to permit the use of the rear end of the hammer

face when large crown corks are to be removed.

The free side of the hammer head is provided with a straight chisel edge 20 which is intended for use as a scraper or peeler.

Pivoted to the frame behind the plate 12, and housed, when not in use, within the middle loop of the frame, is a corkscrew 21, the pivot pin being positioned so that the portion of the hammer-head 16 adjacent the pivot of the cork-screw engages the head of a bottle from which the cork is to be drawn and acts as a fulcrum when starting the withdrawal of the cork by leverage. When thus used, the corkscrew is swung to a reverse position from that shown in Fig. 1 and then inserted into the cork to be extracted. The end 11 of the frame may then be grasped and by pulling upwards with the head 16 engaged with the top of the bottle the cork may be readily extracted.

75 The front loop 13 is provided with the usual notch 22 to embrace the edge of the tin to be opened.

To re-attach a crown cork to a bottle the end 11 is fitted over the cork after the latter has been placed on the bottle, and a firm downward pressure and a twisting motion given to the tool.

80 To function as a fish-scale scraper a loose crown cork is placed within the loop 11 and secured therein by a slight knock. The corrugated edge of the crown cork may then be used as a scraping edge.

The forwardly sloping plane of the hammer-head 16 is at such an angle to the cutting edge of the tin-opener as to prevent injury to the knuckles when hammering or removing tacks.

85 What I claim as my invention and desire to secure by Letters Patent is:—

90 1. In a domestic hand tool, a frame forming a handle, a plate extending transversely through said frame adjacent one end thereof and having an arm one end of which is bent to form a flat plate disposed on one side of said frame, said flat plate extending in a plane at right angles to the plane of said arm and having a face inclined rearwardly with respect to an adjacent surface of said frame, said flat plate cooperating with the adjacent end of said frame in removing a bottle cap.

100 2. In a domestic hand tool, a frame forming a handle, a plate extending transversely

through said frame adjacent one end thereof and having an arm one end of which is bent to form a flat plate disposed on one side of said frame, said flat plate extending in a plane

5 at right angles to the plane of said arm and having a face inclined rearwardly with respect to an adjacent surface of said frame, said flat plate cooperating with the adjacent

end of said frame in removing a bottle cap, and said arm having its front and rear edges 10 recessed to project portions of said face beyond portions of the arm.

In testimony whereof I have affixed my signature.

JOHN JACOB HOELLE.
